LUBRICATOR FOR LAWN MOWERS AND THE LIKE

Kenneth N. Hasenbank, Minneapolis, Minn., assignor to
Toro Manufacturing Corporation, Minneapolis, Minn.,
a corporation of Minnesota

Original design application Apr. 20, 1966, Ser. No. 1,956,
now Patent No. 208,808, dated Oct. 3, 1967. Divided
and this application Feb. 27, 1967, Ser. No. 7,550

Term of patent 14 years

(Cl. D46—1)

Fig. 2

Fig. 4

Fig. 5

Fig. 3

FIGURE 1 is a front elevational view of a lubricator for lawn mowers and the like embodying my new design;

FIGURE 2 is a side elevational view thereof as viewed from the right side of FIGURE 1;

FIGURE 3 is a side elevational view thereof as viewed from the left side of FIGURE 1;

FIGURE 4 is a top plan view thereof;

FIGURE 5 is a bottom plan view thereof.

This is a divisional of Design Application Ser. No. D. 1956, filed Apr. 20, 1966 and now Patent No. D. 208,808.

I claim:

The ornamental design for a lubricator for lawn mowers and the like, substantially as shown.
